UNITED STATES PATENT OFFICE.

GEORGE B. DEACON, OF LOS ANGELES, CALIFORNIA.

SHOOTING GAME.

Application filed July 22, 1927. Serial No. 207,699.

This invention relates to games and pertains to a device whereby the operators may test their skill in projecting a missile in the shape of a ball toward a target by the use 5 of a catapult or pop gun.

The object of the invention is to provide a device of the character above mentioned which may be continuously operated to hurl the missile or missiles, in rapid succession, 10 toward the target or a plurality of targets without the necessity of stopping to reload the catapult or gun, thereby effectively testing the quickness of action of the operator.

The above and other objects of the invention will be more fully disclosed in the following specification and exemplified in the accompanying drawings in which:

Figure 1 is a plan view of the device embodying the invention, the woven wire top 20 or cage being removed to more clearly disclose the essential mechanism.

Figure 2 is a section through the same taken approximately on the line 2—2 of Figure 1, the woven wire top being shown in place and parts of the mechanism being 25 broken away and shown in section.

Figure 3 is a section through the same taken on the line 3—3 of Figure 1.

In carrying out the invention a suitable 30 frame or box 5 is provided which comprises the bottom 6, the side walls 7 and 8 and the front and rear end walls 9 and 10. Mounted in the box 5 and disposed a short distance below the top edges of the sides and ends is 35 a platform 11, the upper surface of which is shaped so as to incline downwardly from the sides and ends to a low point designated at A.

Disposed in a pocket 12 adjacent the wall 40 10 are a plurality of targets 13, 14 and 15 which are identical of construction and operate in the same manner.

Each of the targets comprise a vertically disposed spring pressed strip of metal 16 45 adapted to slide in the guideways 17 which has affixed to its face a suitable symbol or number indicated at 18. The strip 16 is provided with a latch member 19 which normally projects into an aperture 20 formed in wall 10 50 and is held therein by means of a flat spring 21. The lower end of strip 16 is engaged by a spring 22 which tends to force the same upwardly.

A pin 23 provided on its inwardly projecting end with a target button 24 is slidably journaled in an aperture in the wall 10 and

its opposite end abuts against the strip 16 as clearly shown.

By the above recited construction it will be obvious that when the button 24 is struck by a missile the strip 16 will be pushed rearwardly thus releasing the latch 19 and permitting the spring 22 to push it upwardly to present the symbol 18 to view above the wall 10.

The target may be re-set by merely pushing the strip 16 downwardly with the finger until the latch 19 engages with the wall edge of aperture 20.

Secured in the front wall 9 is a catapult or any desired form of missile projecting device 25, the barrel 26 of which points toward the target 14, and arranged at right angles with the mouth of the barrel 26 is a track 75 in the form of a trough 27 which inclines downwardly from the wall 8 toward the barrel mouth.

A second track in the form of a tube 28 is disposed at right angles with the trough 27 and adapted to project into a pocket 29 in the box 5 and is closed at its rear end by a wall 30. The forward end of tube 28 is open, and is pivoted as at 31 adjacent the high end of trough 27 and the tube is adapted to be rocked on said pivot whereby its rear end may be raised or lowered at the will of the operator.

The catapult or missile projecting device has mounted in its barrel 26, a coil spring 32, the rear end of which rests against a stop pin 33 secured in said barrel, and disposed in front of the spring is a washer 34. A rod 35 passes through a aperture in said washer and through the spring its rear end being provided with a hook 36 and its forward end 95 with a button 37 adapted to engage with the washer 34 and also to strike a missile or ball when released for that purpose. The spring 32 is limited in its forward movement of expansion by means of the annular ledge 38 100 formed in the barrel end.

Pivoted at 39 intermediate its ends, to the rear end of the catapult is a lever 40, the upper end of which has pivoted to it one end of a rod 41, the other end of said rod being 105 provided with a hook 42 which engages with the hook 36 of rod 35.

A trigger 43 is pivoted at 44 to the catapult 25 and is provided with a latch 45 adapted to engage with the hook 36 as clearly shown in 110 Figure 2 of the drawings.

The tube 28 has a bracket 46, provided

with a cam slot, 47, projecting from its lower surface and secured in the box 5 are the plates 48 provided with the cam slots 49 which register with slot 47, for the reception of the 5 transverse end 50 of a rod 51 which extends longitudinally rearwardly and is pivoted to the lower end of lever 40 of the catapult.

The partition wall 52 is provided with an aperture 53 which is located opposite the 10 aperture 54 (see Figure 3) formed in the track tube 28 and in order that the aperture 53 may be closed at intervals, a plate 56 is provided and is adapted to project into the path of said aperture.

15 The plate 56 is secured to the free end of a leaf spring 57 which is secured to the box 5, and an arm 58 projects downwardly from tube 28 and is adapted to engage with the spring end to hold the plate 56 away from in front of the aperture 53.

The table 11 is covered by a wire cage 61 in order that the missiles will be prevented from flying out of bounds.

20 In shooting at the target, it is contemplated to use two balls or missiles 59 and 60, although one ball may be employed if desired. When all of the working parts are in the positions shown in the drawings, the ball 60 is in action. The operator manipulates the lever 40 to pull the rod 51 in the direction indicated by the arrow which through the engagement of the end 50 with the cam slots causes the tube 28 to become tilted in a position shown in dotted lines and at the same time the plate 56 is lifted by the action of the 25 spring 57 to close the aperture 53, thus the ball 60 after bounding around is trapped at the low point A as shown in dotted lines at B. The ball 59 upon the inclination of 30 tube 28 rolls into trough 27 and to a position indicated at C in front of the barrel 26. At this instant the operator pulls the trigger 43 which releases the rod 35. The spring 32 then causes the rod to move forward and the button 37 thereon to hit the ball, thus projecting it toward the targets. Upon a reverse ac-

tion of the lever 40 the catapult is again cocked and at the same time the ball at B is permitted to enter the tube 28 when the action may be repeated.

Having thus described my invention what I claim is:

1. A game structure comprising a platform having a low point adapted to deliver balls therefrom; a tiltable track arranged adjacent said platform; a catapult; means for releasing the projecting mechanism of said catapult and means for tilting said track to propel balls delivered thereto from said platform to a point for impulsion by said catapult.

2. A game structure comprising a platform inclined from its edges to form a low point; a tiltable track arranged adjacent said low point; an inclined track disposed angularly with respect to said tiltable track and adapted to form a continuation thereof; a target mounted adjacent said platform; a catapult arranged adjacent the low end of said inclined track; means for operating said tiltable track and means for operating said catapult.

3. A game structure comprising a platform inclined from its edges to form a low point; a plate adapted to close said low point; a tiltable track arranged adjacent said low point; an inclined track disposed angularly with respect to said tiltable tracks and adapted to form a continuation thereof; a target mounted adjacent said platform; a catapult arranged adjacent the low end of said inclined track; means for operating said plate; means for operating said tiltable track and means for operating said catapult.

4. A game structure comprising a platform; a tiltable track arranged adjacent said platform; a catapult; means for releasing the projecting mechanism of said catapult and means for alternately operating said track and setting said projecting mechanism.

In testimony whereof I affix my signature.
GEORGE B. DEACON.
